METHOD FOR DISTILLATION OF OILS

Myron J. Burkhard, Ridgewood, N. J., assignor
to Socony-Vacuum Oil Company Incorporated,
New York, N. Y., a corporation of New York

Application February 24, 1934, Serial No. 712,689

1 Claim. (Cl. 196—94)

This invention has to do with the fractionation of petroleum hydrocarbons and/or similar mixtures, and is specifically directed to method and means for the stripping of light ends from the products of such operation for the improvement of the flash point.

It is customary in the operation of fractionating oils to remove one or more products from the side of the main fractionating tower. These "side cuts" or "side streams" are usually intended for use as finished product, and as such, must meet specifications governing the flash point. To meet such specifications, it is essential that all of the light ends be removed from the side stream.

Present methods for the removal of these light ends make use of a second tower, equipped with bubble cap plates of the usual type. The side stream from the main tower is allowed to flow down over the plates in the side tower, and steam is passed through it in counter-current flow. The vapors and steam from the side tower are returned to the main tower. The amount of vapor to be removed is very small in proportion to the amount of oil to be treated, and the bubble tower is essentially an instrument for the contacting of a large amount of vapor with a proportionately very much smaller amount of liquid. Consequently in the operation of steam stripping, comparatively inefficient contacting of steam with oil occurs, and the result is frequently a very prodigal use of steam for the result accomplished. By the theory of partial pressures, applied to this operation, a small use of steam should be expected, but inspection of quantities from actual operation indicates an excessive steam use.

It has therefore been an object of this invention to devise a more efficient method of contacting steam and oil for the removal of light ends from side stream fractionation products. As a part of this object, there has been the provision of proper means whereby the conceived method may be executed.

For a more perfect understanding of the method and the means whereby it is accomplished, reference is now made to the drawings attached to and made a part of this specification, wherein there are set forth a diagrammatic section of the apparatus used, and several showings of its application.

In the drawings, Fig. 1 shows a section of the apparatus, diagrammatic in form.

Fig. 2 shows how this apparatus may be applied externally to the fractionating tower.

Fig. 3 shows how the method may be applied internally to a fractionating tower.

In Fig. 1, 1 indicates the shell of the side stream stripping tower equipped with an oil inlet 2, an oil outlet 3, and a vapor outlet 4. The lower portion of the tower, adapted to retain a pool of the liquid under treatment to a depth indicated by the surface 5, is provided with a partition 6. This partition is perforate, the total area of such perforations being sufficient to allow free but slow circulation between the two chambers thus formed. The particulars and arrangement of these perforations is immaterial, so long as the above function is accomplished.

In one of these chambers, below the level 5 and adjacent the oil inlet pipe 2 is a steam jet pump 7, of the usual Venturi type, fed with steam through pipe 8, controlled by valve 9. This steam jet pump is arranged to entrain oil from the pool in which it is located, and so located that a substantial portion or all of the incoming oil is so entrained. Its capacity is such that the amount of oil so pumped is greater than the amount of oil to be treated in the same length of time. The oil and steam from the jet pump rise through the mixing tube 10, wherein an intimate and thorough mixture of the steam with the oil is accomplished. The riser preferably ends in an L 11, turned to direct the flow of mixed steam and oil against the shell of the tower. Below this point of discharge there is arranged a plurality of baffles 12, designed to give a flow area whereon the oil may be spread out for the fullest liberation of steam and light end vapors. The last baffle should be so placed that the oil from it falls into the chamber adjacent the oil outlet pipe 3. A mist separator 13, which may be a layer of chemical tile, a dry bubble cap plate, or a grid type of separator, is placed in the top of the tower to prevent the escape of liquid particles entrained in the vapor.

The stripping vessel is equipped with a drain valve 14, and the withdrawal of stripped product is controlled by valve 15.

In some methods of operation it is preferable to withdraw the whole of the liquid on the plate at the desired side cut point, strip it, and return the portion not desired for product to the next plate in sequence in the main tower. This may be accomplished by bringing all of the plate liquid, instead of a fraction of it, to the stripper through line 2. After stripping, the stripper outlet stream flowing through pipe 3 is properly divided by adjustments of valves 15 and 16, and the liquid flowing through valve 16 is returned to the plate in the main tower below the plate from which the liquid was withdrawn. This liquid being entirely free from light ends,

the equilibrium conditions on the plates below which it is returned are bettered, and the entire tower operation may be improved thereby. If desired, this stream may be given a controlled 5 cooling before its return to the tower, thus enabling a closer control on the end point of the product withdrawn above its point of return.

In Fig. 2, it is shown how the method and apparatus may be applied to ordinary fractionating 10 equipment. In this figure, pump 18 forces oil to be distilled through coils in heating furnace 19, and the heated oil is carried through transfer line 20 into fractionator 21. Overhead vapors are taken from tower 21 through line 22, and 15 bottoms through line 23. Stripping steam may be introduced through line 24. A side stream is taken off through line 2, and introduced into stripper 1, equipped similarly to that shown in Fig. 1, and bearing like numerals on each part. 20 In case only the portion desired for side product is withdrawn through line 2, valves 14 and 16 remain closed, and the stripped side product is drawn through valve 15. If it is desired to strip all of the plate liquid at the point of withdrawal, 25 valve 15 will be adjusted to remove the amount required for product, valve 14 will remain closed, and all liquid coming through line 2 and not leaving through valve 15 will pass through valve 16 and pump 17 to be returned to the main fractionating tower.

In Fig. 3, I have shown how the method may be applied on the interior of a tower. In this case, in the main fractionator 25, between bubble trays 26 and 27, a space is set aside and 30 equipped with partition 28, through which vapors may pass by means of chimney 29, equipped with hood 30. Liquid from plate 27 is deposited above partition 28 by pipe 31, and steam jet pump 32, mixing tube 33, and steam control valve 34 exercise the same functions as before, the steamed 35 liquid being discharged on plates 35, which may be as shown, or may be merely a spiral trough along the inside of the tower wall. The steamed oil should be delivered to the side of the oil pool remote from inlet 31, and in the usual case, 40 the relative volume of the tower space is sufficiently great that the flow back to the jet is slow and without great likelihood of short circuiting, so the equivalent of baffle 6 of Fig. 1 may be dispensed with. Stripped oil may be 45 removed through line 36, and the opening of valve 37 will control the amount withdrawn to product, while 38 will control the amount returned to plate 26 through lines 39 and 40. If it is desired, a riser 41 may be attached to pipe

40, so that if the opening of valve 38 is not sufficient, the collected oil may be drawn off without overflowing through the chimney. In case it is not desired to treat all of the oil normally flowing between plate 27 and plate 26, the valve 5 42 in line 31 may be closed partially, admitting to the stripper only so much oil as is desired, the remainder passing through valve 43 and line 44 to the lower plate.

It is of course realized that a commercial interpretation of the apparatus pertinent to this method will not embrace all of the supplementary piping set forth in Fig. 3. This is because at the time of design, the method for use in any one case will probably discard all but one alternate. 10 For instance, if it is decided that the particular unit will operate best when stripping all of the downflowing liquid, pipe 31 will be entirely without valves, and valve 38 and pipes 39 and 40 will be installed. If it is desired to treat only 15 a portion, pipe 31 will be supplied with valve 42, valve 43 and pipe 44 will be used, and valve 38 and pipes 39 and 40 need not be installed. Where pertinent, the control of outflow through line 36 may be accomplished by liquid level control valves after the manner common in the art. In any case, all of the modifications which might be made in any of the apparatus set forth which will still enable its functioning to accomplish the method disclosed are considered to be 20 equivalents and within the scope of the invention except as limited by the following claim.

I claim:

The method of removing low boiling constituents from a mixture of hydrocarbon oils which 25 consists of the following steps: Maintaining a pool of oil, introducing oil to be stripped thereinto, withdrawing oil from the pool adjacent the point of entry of the feed, admixing steam with oil so withdrawn by introducing steam to the 30 oil at the point of withdrawal and passing steam and oil together in a turbulently flowing stream through a passage of substantial length, discharging the steam and oil into a vapor space, and separating steam and light vapors from oil, flowing 35 the oil in films to further effect vapor separation, returning the oil to the pool, controlling said steam to admit solely thereby the entire heat requirements of the process, controlling the amount of oil admixed with steam so that it is in excess 40 of the amount fed to the process per unit time, and withdrawing oil from the pool at a point adjacent the point of entry of oil from the vapor disengaging step.
